UNITED STATES PATENT OFFICE.

CARL P. PAULY, OF SAUK CENTER, MINNESOTA.

AUTOMATIC STOCK-FEEDING APPARATUS.

1,405,431.

Specification of Letters Patent. Patented Feb. 7, 1922.

Application filed May 6, 1921. Serial No. 467,374.

To all whom it may concern:

Be it known that I, CARL P. PAULY, a citizen of the United States, resident of Sauk Center, county of Stearns, State of Minnesota, have invented certain new and useful Improvements in Automatic Stock-Feeding Apparatus, of which the following is a specification.

The object of my invention is to provide an apparatus for use in connection with the manger in a stock barn for automatically delivering a predetermined quantity of feed to the manger at a predetermined time.

15 A further object is to provide an apparatus which will be positive and reliable in its operation and comparatively simple in construction and hence inexpensive to install and maintain.

20 Other objects of the invention will appear from the following detailed description.

The invention consists generally in various constructions and combinations, all 25 as hereinafter described and particularly pointed out in the claims.

In the accompanying drawings forming part of this specification,

Figure 1 is a view of a portion of a cow 30 tie-up and manger, showing my improved stock-feeding apparatus applied thereto,

Figure 2 is a sectional view on the line 2-2 of Figure 1, looking in the direction of the arrow,

35 Figure 3 is a sectional view on the line 3-3 of Figure 1, looking in the direction of the arrow,

Figure 4 is a rear view of the upper portion of Figure 1, showing the feed hopper and mechanism in their discharged position,

Figure 5 is a sectional view on the line 5-5 of Figure 1, looking in the direction of the arrow,

45 Figure 6 is a detail view of the mechanism actuated by the alarm post of the time piece for tripping the feed hopper release.

In the drawing, 2 represents a suitable manger having the usual means 3 for tying stock, such as cows, therein. 4 is a post at one side of the manger and 5 is a hopper extending along the tip-up above the manger and provided with a hinged bottom 6 which, when open, allows the contents 55 of the hopper to drop by gravity into the manger beneath. Pins 7 are provided in

the edge of the hinged bottom 6 and latches 8 are pivoted at 9 on the wall of the hopper and have notches 10 to receive the pins 7. Springs 11 normally hold the latches 8 in engagement with the pins 7. A bar 12 is mounted to engage the upper ends of the latches 8 and is adapted to slide in guides 13 and is normally held in its retracted position by a spring 14. A hammer 15 is pivoted at 16 in position to contact with the bar 12 and move it lengthwise, against the tension of the spring 14. A lever 17 has a head 18 that is pivoted at 19 on the post 4 and has a notch 20 to receive the head 65 of the hammer 15 when it is in its raised position, as indicated in Figure 1. At this time the lever 17 is substantially horizontal and a finger 21 thereon is in engagement with a pin 22 on the upper end of a lever 70 23 that is pivoted at 24 to a bar 25. A spring 26 normally tends to withdraw the lever 23 from engagement with the finger 21 and allow the lever 17 to drop and release the hammer. A bracket 27 is mounted near 80 the lower end of the lever 23 and carries a cam 28, the edge of which is in contact with the lever 23 against the tension of the spring 26. A stud 29 is mounted in the cam 28 and has a flat end portion 30 which engages the fork 31 on the alarm post of the time piece 32. When this cam is in the position shown in Figure 6, with its high side in contact with the lever, the pin on the lever will be held in engagement with the 85 finger 21 on the lever 17 but when the cam is revolved until its low side contacts with the trip lever, the spring 26 will swing the said lever on its pivots sufficiently to release the finger 21, allow the lever 17 to 90 drop and release the hammer 15 which, swinging down to the position shown in Figure 4, will strike the bar 12, trip the latches 8 and release the hinged floor of the hopper, allowing the feed therein to drop 95 100 by gravity into the manger beneath. This movement may take place at any time for which the clock is set. The operator may therefore fill the hopper with the desired feed and leave the barn for a number of 105 hours, knowing that when the clock reaches a certain predetermined point, the mechanism will be automatically tripped and the feed will be delivered to the stock without any attention whatever on the part of the 110 person in charge.

I am aware that automatic stock feeders

have heretofore been devised but my invention or improvement consists in simplifying and making more positive and reliable the operation of the parts, as evidently a device 5 of this kind must operate at the time desired or it would be wholly useless for the purpose designed. I have accomplished this with the simple, strong and durable device herein shown.

10 I claim as my invention:

1. The combination, with a manger, of a feed hopper supported above the same and having a hinged bottom, latches pivoted adjacent to said hinged bottom and engaging 15 the same for normally locking it in its closed position, a sliding bar mounted to engage and trip said latches, a hammer for engaging said bar, a trip mechanism for moving said hammer to its actuating position, and a time piece for operating said trip mechanism at a predetermined period.

2. The combination, with a manger, of a feed hopper and a hinged bottom therefor, mechanism for normally locking said bottom in its closed position, a hammer mounted to move said locking mechanism to its release position, a lever having a head to normally receive and support said hammer, a trip lever mounted to engage said hammer-supporting lever and normally lock it in its supporting position, and a time piece having means for engaging and moving said trip lever to its release position.

3. The combination, with a hopper having a discharge opening and a floor normally closing said opening, a locking mecha-

nism for said floor, an actuating hammer for said locking mechanism, a lever having a head to receive said hammer and normally support it, a trip lever for engaging 40 said hammer-supporting lever and holding it in its locking position, and a time piece having a cam mounted to engage said trip lever and operate it at a predetermined period.

4. An automatic stock feeder comprising a hopper provided with a discharge opening, and means for normally closing said opening, a mechanism for tripping said closing means and comprising a tilting hammer 50 and a locking lever therefor, a trip lever engaging said locking lever, a revoluble cam having a high surface to engage said trip lever and hold it in its locking position, said cam having a stud and a time piece 55 having an alarm post provided with a socket to receive said stud, the revolution of said stud revolving said cam to present its low surface to said locking lever at a predetermined period.

5. The combination, with a manger, of a feed hopper supported above the same and having a hinged bottom, means for normally locking said hinge bottom in its closed position, a sliding bar for tripping said locking means, a hammer mounted to engage and actuate said bar, and a time piece operated trip mechanism for moving said hammer to its actuating position.

In witness whereof, I have hereunto set 70 my hand this 3rd day of May, 1921.

CARL P. PAULY.
